ATTORNEY

UNITED STATES PATENT OFFICE.

LOUIS WOJIDKOW, OF BROOKLYN, NEW YORK.

DESIGN FOR A STAND FOR CHAFING-DISHES.

SPECIFICATION forming part of Design No. 26,435, dated December 22, 1896.

Application filed November 13, 1896. Serial No. 612,035. Term of patent 3 $\frac{1}{2}$ years.

To all whom it may concern:

Be it known that I, LOUIS WOJIDKOW, a citizen of the United States, residing in Brooklyn, county of Kings, and State of New York, 5 have invented and produced a new and original Design for Stands for Chafing-Dishes, of which the following is a specification, reference being had to the accompanying drawing, which shows the same in perspective.

10 The leading feature of my design consists of inwardly-curved standards or legs, the upper portions of which are broadened and the lower portions plain and terminating in ornamented feet, and a lower ornamented sup-

15 porting-ring having curved arms or brackets extending therefrom to said standards.

A is an upper supporting-ring, from which

depend inwardly-curved legs or standards B, the upper portions of which are broadened and ornamented, as shown at b, and the lower 20 portions of which are plain and terminate in the ornamented feet c.

C is a lower ring, ornamented as shown, and from which extend the curved brackets or arms D, the latter being ornamented and 25 broadened at their outer ends and joined to the legs B.

What I claim is--

The design for a stand for chafing-dishes, as herein shown and described.

LOUIS WOJIDKOW.
